UNITED STATES PATENT OFFICE.

ALOIS AUGUST RITTER, OF RACINE, WISCONSIN, ASSIGNOR TO HARTMANN TRUNK COMPANY, OF RACINE, WISCONSIN, A CORPORATION OF WISCONSIN.

ELECTRIC-IRON HOLDER.

Application filed February 19, 1923. Serial No. 619,997.

To all whom it may concern:

Be it known that I, ALOIS AUGUST RITTER, a citizen of the United States, and resident of Racine, in the county of Racine and State of Wisconsin, have invented new and useful Improvements in Electric-Iron Holders, of which the following is a description, reference being had to the accompanying drawings, which are a part of this specification.

This invention relates to a holder for electric irons, and particularly to a holder designed to support an electric iron or the like within a wardrobe trunk.

It has become the practice recently to equip wardrobe trunks with electric irons, but difficulty has been experienced in preventing the iron from moving about within the trunk while the trunk is in transit.

It is therefore the particular object of this invention to provide means whereby an electric iron or the like may be conveniently mounted within a wardrobe trunk and prevented from becoming displaced, even though the trunk be subjected to rough usage. The iron holder forming the subject matter of this invention also contemplates the provision of means whereby the iron may be quickly and easily released when it is desired to use the same.

The novel combination, construction and arrangement of parts of this invention will be made more apparent as the description proceeds, especially when considered in connection with the accompanying drawings wherein;

Figure 1 is a fragmentary front elevational view of a wardrobe trunk, partly in section, showing this improved iron holder in place;

Fig. 2 is a top plan view of the iron holder, part of the iron being shown in section;

Fig. 3 is a transverse sectional view, taken substantially on the plane indicated by the line 3-3 in Fig. 2; and,

Fig. 4 is a sectional view, taken substantially on the plane indicated by the line 4-4 in Fig. 2.

Referring now more particularly to the drawings wherein like reference characters indicate like parts, it will be seen that the reference character 10 indicates a wardrobe trunk which may be of any suitable type of

construction and provided with a plurality of drawers 11.

The iron holder consists of a base 12 which may be formed of a board or the like, this base member being suitably shaped to fit in one of the compartments 13 of one of the drawers 11.

Projecting upwardly from the base 12 is an upright or standard 14, this upright being provided with a pair of spaced slots 15. The clamping member consists of a transverse strip or member 16, one end of which is designed to enter one of the slots 15, depending upon the size of the iron. The other end of the clamping member 16 is provided with an elongated slot 17 for receiving the clamping bolt 18, pivoted as at 19, to a bracket 20 secured to the base 12. A thumb nut 21, threaded on the clamping bolt 18 is adapted to engage the clamping member 16.

The reference character 22 indicates the iron, and the reference character 23 the U-shaped portion of the iron handle which supports the grip 24.

Secured at right angles to the clamping member 16 is a secondary clamping member 25, which member is formed with an open ended slot 26, adapted to engage one shank of the U-shaped handle member 23, as clearly illustrated in Figs. 2 and 4. A chain or other flexible means 27 is connected respectively to the bracket 20 and the iron clamping member to prevent the same from becoming lost.

In practice the secondary clamping member 25 is caused to engage, by means of its slot 26, the handle portion 23, while the transversely extending portion of the clamping member is so manipulated that one end thereof is projected into one of the slots 15 of the upright 14 and the other end arranged to be engaged by the clamping bolt 18, which enters the slot 17.

The thumb nut 21 is then rotated to cause the clamping member 16 to bear down tightly against the iron, whereupon the iron will be firmly held to the base 12 and prevented from moving around the trunk. Obviously the base 12 may either be fastened to the floor of the drawer in which it is placed, or it may be caused to firmly engage the same by fitting snugly therein.

From the foregoing description it will be

immediately apparent that the iron may be secured in place or removed with facility, and when secured in place by the iron holder it will be securely held against accidental displacement.

Obviously modifications may suggest themselves, and to this end reservation is made to make such changes as may come within the purview of the accompanying claims.

Having thus described the invention what is claimed is:

1. In an iron holder of the class described a base member, an upright projecting therefrom, said upright being formed with a slot, a clamping bolt pivotally secured to said base member and a removable clamping member adapted to engage the slot of said upright and to be clamped against the iron by said pivoted bolt member.

2. An iron holder of the class described comprising a base member, an upright mounted on said member and provided with a plurality of slots, a pivoted clamping bolt

mounted on said base member and an iron clamping member adapted to engage one of said slots and to be engaged by said clamping bolt, for the purpose described.

3. In an iron holder of the class described a base member, an upright member secured to said base member, said upright member being formed with a plurality of slots, a clamping bolt pivotally mounted on said base member and an iron clamping member comprising a transverse clamping portion and an angular clamping portion, said transverse clamping member being adapted to engage at one end with one of said slots, the other end of said member being slotted to receive said clamping bolt, said angular clamping member being formed with an open ended slot to engage the handle of the iron.

In testimony whereof, I affix my signature.

ALOIS AUGUST RITTER.
